LOCK

Peter Boyko, Bronx, N. Y.

Application March 23, 1932, Serial No. 600,588

1 Claim. (Cl. 70—14)

The invention relates to locks which require for their successful manipulation in throwing the bolt into unlocked position a necessity of employing not only the proper key in case a 5 key-controlled form of the invention is employed, or the knowledge of the proper combination in case a combination form of the device is used, but also requires a knowledge on the part of the operator as to how the key or controlling knob of the combination must be rotated 10 in order to throw the bolt.

Accordingly, the primary object of the invention is to provide a simple form of safety lock which can be fitted to opposite sides of doors 15 and other supports having different thicknesses and which can be readily operated by a person who has the knowledge as to how the proper control agency, be it either key or combination control knob, should be actuated.

Still another object of the invention is to provide such form of dual controlling feature lock which can be readily reorganized so as to change its tumbler arrangement and thus work with a 20 different form of key or with a different dial combination.

Broadly these objectives are attained by providing a two part construction fitted to opposite sides of the door. One part comprises a tumbler barrel which may be either key actuated or dial 25 controlled as is well known in locks of this character, and the other part providing a lock casing containing a sliding bolt. The bolt is actuated by a break toggle arrangement of levers contained in the casing, one pivoted to the bolt 30 and the other pivoted in the casing and actuated from a connecting bar in turn actuated from the tumbler barrel. The levers are arranged in such way that the barrel controlled lever is free to turn in either direction idly and 35 without throwing the bolt when the controlling barrel is indiscriminately rotated by an unauthorized person, or even by a person who has the proper key or knows the proper combination to operate the barrel. The disclosure features 40 a construction of the operating levers organized so that a notch in the end of one can be rotated into engagement with the end of the other and then by a reverse movement of the barrel when this end to end engagement has 45 been effected will shift the bolt into its unlocking position.

Various other objects and advantages of the invention will be in part obvious from an inspection of the accompanying drawing and in 50 part will be more fully set forth in the follow-

ing particular description of one form of mechanism embodying the invention, and the invention also consists in certain new and novel features of construction and combination of parts hereinafter set forth and claimed.

In the accompanying drawing:

Fig. 1 is a view partly in vertical section of a preferred embodiment of the invention with part of the cover plate of the lock casing removed, to expose to view the bolt and associated parts; and with part of the casing broken away to expose the rear or inner end of the actuating knob; and showing the parts in full line with the bolt in locked position;

Fig. 2 is a view of the inside of the removable cover plate;

Fig. 3 is a view corresponding to the showing in Fig. 1 with the cover plate in position; the bolt shown in dotted outline and shifted into its unlocked position and viewing the lock casing from the side engaging the support as shown in Fig. 4; and

Fig. 4 is a transverse sectional view taken through the casing on the plane indicated by the line 4—4 of Fig. 3 and showing the casing 25 assembled on one side of a support in operative engagement with the tumbler barrel inset into the opposite side of the support.

It is understood that the device herein disclosed comprises two major parts, a lock casing 30 10 and a tumbler barrel 11, mounted in position on a support 12, such as a door shown in Fig. 4, and preferably inset into opposite faces of the support as is well known in mounting locks of this character in place.

In the illustrated form of the invention the barrel 11 includes the usual tumbler controlled cylinder 13 which is rotated when the proper key 14 is inserted into the key slot 15 access to which is provided on the outside of the support 40 12. While the device has been disclosed in connection with this type of tumbler controlled barrel, it is understood that barrel 11 may be of the dial controlled type in which the barrel 13 is rotated only when an exposed dial knob 45 has been rotated the prescribed number of degrees and in the prescribed direction for which the combination is set as is usual with safe locks. In either case, when the barrel is properly rotated it in turn rotates a spacing bar 16 50 which projects towards and into the lock casing 10 as hereinafter described. It is understood that the spacing bar 16 is of the usual length so as to reach between the major parts when mounted in supports 12 of varying thick- 55

nesses and that any excess in length of the spacing bar may be cut off if necessary in mounting the lock in place.

The lock casing 10 comprises essentially a hollow box 17 opened along its inner side which inner side is closed by means of a cover plate 18. The casing as a whole is mounted on the inner side of the support 12 by means of screws passed through the screw apertures 19 in the casing and cover plate. The cover plate 18 is provided with an opening 20 extending therethrough and which opening provides a bearing for the hub 21 of a notched end lever 22 which extends laterally across the inner side of the cover plate 18. It is a feature of this disclosure that when the cover plate 18 is removed it carries with it the notched lever and can thus be removed from the lock casing without necessity of disconnecting the lever from any of the bolt actuating parts carried by the casing and hereinafter described. The casing is provided with guide bars 23 formed integral with its bottom and slidably mounted on these bars is a bolt 24. This bolt is provided with projecting fingers 25 designed to engage in apertures in keepers 26 secured to a mounting plate 27 as is usual in constructions of this character. The bolt is normally urged into its locking position by means of spring 28.

Pivotedly mounted on one side of the bolt 24 is a thrust member 29 provided on opposite sides with balancing springs 30 and 31 which tend normally to maintain its free end 32 in the path of rotary movement of the lever 22. The end of the lever 22 is provided at its free end with an angularly disposed notch 33 higher on one side than on the other as particularly shown in Figs. 2 and 3. Hub 21 of lever 22 is provided at its center with a bar slot 34 into which is intruded the end of bar 16 as particularly shown in Fig. 4. The inclination of the sides forming the slot 33 are so disposed that when the lever 22 is rotated in anti-clockwise direction as indicated in dotted lines in Fig. 1, the lever simply bears against the upper side of the thrust member and working against spring 31 simply moves idly past the lever when turned in this direction without affecting the thrust member and without affecting the position of the bolt. It is likewise true that the lever 22 can be rotated in a clockwise direction and in the absence of knowledge as to where it should be stopped in this rotary movement, it can simply be turned idly and will similarly pass the thrust member without shifting the bolt 24 when turned in this direction. However, if the key 14 or the controlling dial of the combination controlled barrel be rotated carefully in the direction to turn the lever 22 in Fig. 1 in a clockwise direction and until the notched end has shifted to a position where the free end of the thrust member is in engagement with the slot 33 the parts will then be in the position indicated in the upper dotted line showing in Fig. 1 and in the showing in Fig. 3. Then by a reverse or anti-clockwise movement of the key or dial knob the notched end 33 of the lever 22 bears endwise against the thrust member 29 to shift the same from the upper, dotted line position shown in Fig. 1 into the unlocked dotted line position shown in Fig. 3. It will be seen that the lever 22 and thrust member 29 form in effect a toggle construction, as shown in Fig. 3, which tends to straighten out as the lever 22 is rotated counter-clockwise thus shifting the bolt

into its unlocking position against the tension of its return spring 28.

Rerotating lever 22 clockwise from its position shown in Fig. 3, releases tension on the thrust member and permits the spring 29 to restore the lock to its normal locking position shown in Fig. 1. As soon as the thrust member is free from the pressure of the actuating lever 22 the springs 30 and 31 act to restore the thrust member into its normal inoperative position with the end 32 projecting towards the hub 22 as shown in full lines in Fig. 1.

It is understood that the lock casing may contain other features such for instance as the bolt shifting knob 38 mounted for rotary movement in the bottom of casing 10 and provided on its inner side with a finger 35 designed to bear on shoulder 36 of the bolt to shift the bolt into open position against the tension of spring 28. The casing may also be provided with a manually controlled plunger 39 for locking the bolt in its unlocked position, as shown in Fig. 3. A screw 40 passed through aperture 41 in cover plate 18 and engaging in spacing lug 42 acts to secure the cover plate to the casing.

In marketing devices of the type herein disclosed, it is possible to manufacture the lock casing and its contained parts as a standard unit which can be combined with tumbler barrels of different types and wherein the tumblers can be rearranged as is well known in tumbler locks of this character. As the spacing bar 16 can accommodate itself to varying distances at which the lock casing and barrel may be spaced apart, it is possible to mount the construction herein disclosed in doors and other parts of various thicknesses and even on a support so thick that it would be impractical to provide a key sufficiently long to extend through the same to engage the lock casing. It is, of course, possible to change the tumbler combination so that the device can be operated with a key differing from the key originally used and this resetting of the tumbler parts can be attained without making any change in or even dismounting the bolt containing casing. It is noted that the hub 21 is mounted fixed axially relative to the axis about which it turns and there is thus assured a registering of the free ends of lever 22 and the thrust lever which is in no way dependent upon the accuracy of fit of the controlling key 14 in its slot 15 and in fact is in no way dependent upon the key except insofar as the key controls the rotation of the barrel in which it is contained.

I claim:

A lock including a casing in the form of a hollow box open at its inner side, said box provided on the inner side of its bottom with integral guide bars and with an integral bolt stop, a bolt slidably mounted in the guide bars and provided with projecting fingers, a bolt spring acting on the bar and urging it towards said stop, a manually actuated bolt shifting knob mounted for rotary movement in and extending through the bottom of the box and provided with a lever adapted to engage the bolt for moving it into its open position against the tension of said spring, a pointed end lever pivotally mounted on the side of the bolt facing the open side of the box and constituting a thrust member, a pair of studs positioned on opposite sides of the axis of rotation of the lever, a pair of balancing springs with one end of each coiled about one of the studs and hav-

ing their free ends bearing on opposite sides of the thrust lever, a cover plate for closing the open side of the box, a notched end lever provided with a hub journalled for rotary movement about a fixed axis in the cover plate, said hub provided with a slot adapted to receive a spacing bar of a tumbler lock, said lever extending across the inner side of the cover plate and removable bodily therewith without affecting the bolt and its associated parts carried by the box, the free end of said lever provided with an

angularly disposed notch higher on one side than on the other to form a shoulder and disposed when the lever is rotated in one direction to bear on the thrust lever and move past the same and when moved in the opposite direction to cause the end of the thrust member to engage in said recess and when reverse therefrom to engage said shoulder to shift the bolt into its open position and against the tension of the bolt spring.
